CLAIM

The ornamental design for a ventilated work station, as
shown and described.

DESCRIPTION

FIG. 1 is a front elevation view of a ventilated work
station showing my new design; the rear being plain and
unornamented,

FIG. 2 is a right-side elevational view thereof, the left

side being a mirror image thereof, and

FIG. 3 is a front perspective view thereof.

FIG. 1

FIG. 2

FIG. 3
